E. P. O'LEARY.
NECKTIE AND HOLDER.
APPLICATION FILED JAN. 31, 1907.

903,400.

Patented Nov. 10, 1908.

UNITED STATES PATENT OFFICE.

EDWARD P. O'LEARY, OF LOS ANGELES, CALIFORNIA, ASSIGNOR OF ONE-HALF TO DANIEL O'LEARY, OF LOS ANGELES, CALIFORNIA.

NECKTIE AND HOLDER.

No. 903,400.

Specification of Letters Patent. Patented Nov. 10, 1908.

Application filed January 31, 1907. Serial No. 255,142.

To all whom it may concern:

Be it known that I, EDWARD PATRICK O'LEARY, a citizen of Canada, residing at Los Angeles, in the county of Los Angeles and State of California, have invented a new and useful Necktie and Holder, of which the following is a specification.

It is of the objects of this invention to provide at a minimum expense a necktie having the appearance of a hand-tied tie; to provide such a tie with a minimum amount of tie material; to enable the wearer to quickly, readily and conveniently form and fasten the tie material in place on the holder; to so construct the holder as to give a minimum amount of material the fullness requisite to give the appearance of the use of a large amount of material; to enable the wearer to use a minimum of tie material in various positions on the holder so as to at different times bring into exposed position previously unused portions of the tie material until practically all of the tie material has been thus used.

Other objects and advantages may appear from the subjoined detailed description.

The invention may be applied in various forms.

The accompanying drawings illustrate the invention in some of the forms in which it may be embodied.

Figure 1 is a front view of a tie detached, illustrating the invention in one of its forms. Fig. 2 is a rear view of the same tie detached. Fig. 3 is a vertical mid-section on lines x^3-x^4 , Figs. 1 and 2. Fig. 4 is a view of another form of tie embodying this invention. Fig. 5 is a view of a tie holder and fastener separated from each other. Fig. 6 is a view of a holder adapted for forming a bow-tie. Figs. 7 and 8 are details respectively of two forms of tie rings, one being solid and the other open, and either of which may be used in the forms shown in Figs. 1, 2, 3, 4 and 5.

1 designates the body of the tie-holder, the same being made of sheet material as metal, celluloid, rubber, papier-mâché, or the like, and formed in two arms 2, 3, to insert under the flaps of a turn-down collar as is the case in many necktie holders heretofore in use. Said arms are perforated as at 4, two perforations being applied near the end of each of the arms and near the opposite edges thereof. 5 designates loops which may be

in the form of wire staples inserted through said perforations and forming a loop between the opposite perforations at each end of the arm, as indicated in Figs. 2, 3 and 5.

6 is a fastener which may be made of material corresponding to that of the body, and is likewise provided with two arms 7, 8, narrower than the arms 2, 3, and adapted to insert under loops 5 thereby to be held in place on the body 1. Said fastener is provided with a tongue 9 bent rearwardly from the middle of the fastener to support a collar-button clamp 10 of any construction ordinarily employed heretofore for gripping the collar-button to hold the tie-holder in place.

The body 1 with its arms 2, 3, and the fastener 6 with its arms 7, 8, are curved substantially in the arc of a circle, and the tongue 9 is located in the middle thereof and at the lower portion of the bend of said arc.

11 is a retaining limb extending downwardly from the middle of the body 1 in the form of a device adapted for four-in-hand or for drawn ties, as illustrated in Figs. 1, 2, 3, and in Fig. 4. 12 is a corresponding limb extending downwardly from the middle of the fastener 6.

13 is a retaining ring which may be a solid ring as shown in Fig. 7, or an open ring as shown in Fig. 8, the purpose of which is to retain the free end of the tie material 14, as shown in Fig. 4.

The downward extensions or retaining limbs 11 and 12 may be omitted in a holder intended for bow-ties, which holder is illustrated in Fig. 6.

In practical use the tie, either four-in-hand or drawn tie, may be formed by first removing the fastener 6 from the loops 5 and then forming over the same the requisite folds for the tie desired. The manner of doing this will be readily understood by anyone familiar with the art of making knots. One end 15 of the tie material will be brought over the body 1 and held on the retainer 11 while the tie material is wrapped about the body to form the required knot.

In the case of a four-in-hand tie illustrated in Figs. 1, 2, 3, the ring 13 will be bent up in front of the body as indicated in Fig. 3, and covered over by the tie material. In this position it serves to hold outward the tie material forming the knot to give the same an apparent fullness. In the drawn

knot shown in Fig. 4 the tie material will be run through the ring as indicated. Thus the ring serves to retain the tie material.

The downward extension 11 of the body is 5 preferably lobe shaped, as shown, having a narrow portion or neck 16 between its lower end and the body 1, said neck being of less diameter than the inside diameter of the ring 13 so that said ring will loosely fit on the 10 neck or will be held thereon by the lobe or lower portion of the extension or retainer. The material of the body 1 and retainer 11 is of a resilient nature as is common with sheet material above mentioned, so that the 15 ring may readily be placed in position for bending the lobe into a form to pass through the ring and then allow the lobe to assume its flat form again.

It is to be understood that the body 1 and 20 fastener 6 are curved from the middle rearwardly, as indicated in Fig. 3 and as is common with necktie holders in order that the same may fit the neck when the arms 2, 3 and 7, 8 have been inserted beneath the 25 folds of a turn-down collar.

In Fig. 3, 17 designates a collar-button on 30 which the clamp 10 is fastened. It is apparent that the tie may be manufactured and sold complete, or that the holder including the body 1 and fastener 6 with their adjuncts 35 may be sold separately from the tie material.

In practical use, when the tie has been formed, the wearer will adjust the tie in place and remove it therefrom in the usual 35 manner common with necktie-holders having a collar-button clamp.

The tongue 9 on which the collar-button 40 clamp 10 is fastened projects rearwardly from the fastener 6, thus to give an apparent greater depth to the knot so that a tie made of comparatively thin and scanty material may have the apparent fullness of a tie in which a large amount of material has been used.

45 Whenever a tie becomes soiled or dingy, or the wearer desires to renew the appearance from any cause whatever, the fastener 6 may be removed by slipping its resilient

arms 7, 8 out from under the loops 5 and then unwrapping the tie material, rewrapping the same on the body 1 and its arms to bring a new surface into view, and thereupon the fastener will be again replaced; whereupon the tie may be used as before.

The downwardly-projecting retainers 11 55 and 12 of the main body 1, and the fastener 6 serve to hold the tie material positively in place centrally of the necktie-holder.

What I claim is:

1. A necktie holder comprising a body 60 provided with arms and a downwardly-extending retainer, loops on said arms, and a fastener provided with a downwardly-projecting retainer and with arms inserted through said loops. 65

2. A necktie holder comprising a body provided with arms and a downwardly-extending retainer, loops on said arms, a fastener provided with a downwardly-projecting retainer and with arms inserted through said 70 loops, and a ring around said retainers.

3. A necktie holder comprising a body provided with arms, a fastener detachably secured to the body and provided with arms and having a tongue bent rearwardly from 75 the upper edge of said fastener, and a collar-button clamp on said tongue.

4. The combination with a body formed of sheet material and provided with arms and a downwardly-extending lobe-shaped 80 retainer, of loops in said arms, tie-forming material looped around said body and arms, a fastener provided with arms and a downwardly-extending retainer and having its arms inserted through the loops, and a ring 85 around said retainer and said material, a portion of the tie material being between the body and the fastener.

In testimony whereof, I have hereunto set my hand at Los Angeles California this 90 16th day of January, 1907.

E. P. O'LEARY.

In presence of—

JAMES R. TOWNSEND,
M. BEULAH TOWNSEND.
